UNITED STATES PATENT OFFICE.

WILLIAM CAMPBELL, OF DETROIT, MICHIGAN.

DISH-WASHING MACHINE.

1,178,213.

Specification of Letters Patent.

Patented Apr. 4, 1916.

Application filed October 14, 1915. Serial No. 55,750.

To all whom it may concern:

Be it known that I, WILLIAM CAMPBELL, a citizen of the United States of America, residing at Detroit, in the county of Wayne 5 and State of Michigan, have invented certain new and useful Improvements in Dish-Washing Machines, of which the following is a specification, reference being had thereto in the accompanying drawings.

10 This invention relates to a dish washing machine, and the primary object of my invention is to provide a novel washing machine which may be utilized as a kitchen table, even while the machine is in operation, 15 the kitchen table being convertible into a dish washing machine by simply raising a movable top section of the table, placing dishes in the machine, and then placing the machine in operation. This object of my 20 invention is attained by a strong and durable structure possessing sufficient rigidity to permit of the top of the machine being used for various purposes and particularly as a table top.

25 Another object of my invention is to place an electrically operated washing and rinsing machine below the top of a table whereby it will occupy a comparatively small space in a kitchen or culinary department and permit 30 of dishes and cooking utensils being thoroughly washed and rinsed when occasion requires. This object is attained by a washing machine embodying a suitable casing having a drain board or bottom terminating 35 in a basin, and in the basin is means for agitating the contents thereof and projecting the contents upon dishes and utensils placed within the casing.

40 A further object of my invention is to provide a combined kitchen table and washing machine wherein the parts are constructed with a view of reducing the cost of manufacture and at the same time retaining those features by which the parts of the machine 45 may be easily assembled and economically operated.

With the above and other objects in view, the invention resides in the novel construction, combination and arrangement of parts 50 to be hereinafter specifically described and then claimed, and reference will now be had to the drawings, wherein—

Figure 1 is a longitudinal sectional view of a dish washing machine in accordance 55 with my invention; Fig. 2 is a horizontal sectional view taken on the line II—II of

Fig. 1; Fig. 3 is a front elevation of the dish washing machine; Fig. 4 is a cross sectional view taken on the line IV—IV of Fig. 3, showing the lid or closure of the machine 60 in a raised position and partly broken away, and Fig. 5 is an enlarged detail sectional view of a bearing, illustrating a packing for the same.

In describing my invention by aid of the 65 views above referred to, I desire to point out that the same are merely illustrative of an example whereby my invention may be applied in practice, and I do not care to confine the invention to the precise construction and arrangement of parts shown. The 70 following description is therefore to be broadly construed as including substitute constructions and arrangements of parts which are the obvious equivalent of those to 75 be hereinafter referred to.

In the drawings, 1 and 2 denote sets of legs or uprights, preferably made of angle iron, and the upper ends of the legs 1 and 2 are connected by longitudinal side frames 80 3 and 4, also made of angle iron.

Suitably connected to the lateral flanges of the frames 3 and 4 contiguous to the legs 1, is a permanent top section 5 in the form of a board incased in a metallic sheeting 6 85 which protects the board and presents a surface that cannot be easily injured when meat or vegetables are cut upon the top section or hot utensils placed thereon. The permanent top section has its longitudinal 90 edges equidistant from the legs 1, thereby overhanging one end of the rectangular structure formed by the legs 1 and 2 and the side frames 3.

Extending toward the legs 2 are bearing 95 members 7, carried by the legs 1 and connected to said bearing members, the legs 2 and the side frames 3, are the side walls 8 of substantially a rectangular metallic casting, said casing having an open top, a vertical end wall 9, an inclined end wall or deflector 10, an inclined drainboard or bottom 11, and a transverse semi-cylindrical basin 12 at the lower edge of the drain bottom or board 11. The inclined end wall 10 is disposed at a tangent relative to the basin 12 and the upper edge of said inclined wall is offset, as at 13, and provided with a transverse flange 14 secured to the edge or underside of the permanent top section 5. 110

Hinged or otherwise connected to the side frame 3, as at 15, is a movable top section 16

serving functionally as a lid or closure for the casing, and when closed, as a continuation of the permanent top section 5, whereby these two sections will coöperate in providing a table top just as useful if not more so than the ordinary kitchen table top. The movable top section 16 is incased by a metallic sheeting 17 formed at the inner side of the movable top section to provide flanges 18 adapted to engage the inner sides of the walls 8, 9 and 10 and correctly position the movable top section when closed. When the movable top section 16 is open, its opening movement is limited by a stop member 19 carried by the overhanging edge of the movable top section, as best shown in Fig. 4, said stop member preventing the movable top section from injuring a wall or swinging so far open that it can not be conveniently closed from the front side of the machine.

The confronting sides of the walls 8 of the casing are provided with inclined angle brackets 20 adapted to support a wire tray 21 or a foraminous holder for dishes or utensils. The inclined bottom or drainboard 11 of the casing is also adapted to support a wire tray or foraminous holder 22 constructed and partitioned for holding various kinds of dishes or utensils, whereby the surfaces of the dishes or utensils may be subjected to a washing or rinsing action. For instance, the tray or holder 22 has receptacles or cages 23, formed of wire or perforated metal by which spoons, knives, forks or other culinary implements may be supported and subjected to a washing or rinsing action.

Journaled in the bearing members 7 is a driven shaft 24 disposed longitudinally of the basin 12 and mounted upon said shaft, 40 within the basin 12, is an agitating and projecting-two-blade member 25, said member having the longitudinal outer edges thereof disposed at an angle, as indicated at 26, whereby water or a cleansing liquid within 45 the basin 12 will be projected against the inclined wall 10. An end of the driven shaft 24 protrudes from the rear side of the machine and is provided with a large grooved wheel 27 for a belt 28 trained over a small 50 pulley 29 on the armature shaft of an electric motor 30 secured to a bracket 31, carried by the leg 1 at the rear side of the machine. A switch 32 controls the operation of the 55 motor 30 and said motor may be operated by an ordinary electric lighting circuit or from any suitable source of electrical energy.

The basin 12, at the forward end thereof, has a drain or outlet port 33 normally closed by a plug or stopper 34 on the lower end of 60 a rod 35. The rod 35 is offset to provide clearance for the driven shaft 24 and said rod extends through a tube 36, carried by the inclined wall 10 of the casing. The upper end of the rod 35 is loosely connected to 65 a crank 37 on a shaft 38, journaled in a sec-

tor bearing 39 carried by the leg 1 at the front side of the machine. The shaft 38 has an operating handle or crank 40 in frictional engagement with the sector bearing 39 and by adjusting the handle 40 the plug or stopper 34 may be raised and lowered.

To insure a non-leakable connection between the driven shaft 24 and the rear wall of the casing, said shaft has a packing collar 41, as best shown in Figs. 1, 4 and 5, said collar snugly fitting the driven shaft and preventing water or washing liquid from leaking through the bearing of said shaft.

To place the machine in operation, the movable top section 17 is raised, trays of 80 dishes placed within the casing, the top section 17 closed and then the switch 32 turned on to start the motor 30 and impart a rotary movement to the agitating and projecting member 25 within the basin 12. With water 85 or a cleansing liquid in the basin 12 and the lower part of the casing, the water is projected on to the dishes within the trays or holders 21 and 22 and after this operation has been carried on for a predetermined 90 time, the water can be removed from the basin 12 through the drain or outlet port 33 and a fresh supply of water placed within the casing for rinsing the dishes therein.

I attach considerable importance to the 95 inclined drain board and bottom 11 and the basin 12 of the casing, as all water and matter drains into the basin and the water may be removed or repeatedly used. The basin however is of such depth as to collect foreign 100 matter and it is possible to thoroughly cleanse and flush the basin after the washing machine has been used.

The inclined end wall 10 coöperates with the member 25 in projecting water or a 105 washing solution over the dishes, and when a washing powder or a suitable detergent is used in the water the member 25 causes the detergent to thoroughly commingle with the water.

Ordinarily a receptacle is placed beneath the drain or outlet port 33 of the basin 12 to receive water therefrom, after the machine has been used, but in some instances a hose may be attached to the drain or outlet port 115 to conduct the contents of the basin direct to a sewer.

The casing of the machine affords a compartment that may be used for a variety of purposes, when devoid of dishes, and it may be found convenient to allow the dishes to remain in the compartment, after having been washed, until such time as it is desired to use the same. With the movable top section of the casing closed, it coöperates with the permanent top section 6 in providing a 120 large protected area that may be used similarly to an ordinary kitchen table top.

What I claim is:—

A dish washing machine comprising a 130

frame, a top section supported thereby, a casing supported by said frame and having an inclined wall extending inwardly from one end of said frame to said top section, a 5 basin forming part of said casing and having a drain port at an end thereof, a stopper for the basin drain port, a rod connected to said stopper extending through the inclined wall of said casing beneath said top section, 10 a shaft carried by said frame between said

top section and the inclined wall of said casing and having a crank connected to said stopper rod, and means on said frame to hold said shaft in adjusted position.

In testimony whereof I affix my signature 15 in presence of two witnesses.

WILLIAM CAMPBELL.
